SKIVING MACHINE

Lewis J. Bazzoni, Swampscott, Mass., assignor to
 United Shoe Machinery Corporation, Paterson,
 N. J., a corporation of New Jersey

Application December 30, 1937, Serial No. 182,546

3 Claims. (Cl. 12—49.1)

This invention relates to skiving machines and is illustrated as embodied in a machine for skiving the projecting margins of covers applied to the rear and side faces of heels to uniform widths.

5 It is an object of the present invention to provide an improved machine of the general type disclosed in United States Letters Patent No. 2,029,304, granted February 4, 1936, on an application filed in my name. With the above object 10 in view, and in accordance with a feature of this invention, there is provided a skiving machine comprising a cutter rotatable about an axis and having a plurality of circumferentially spaced cutting edges a portion of each of which is equidistant from said axis, and an anvil having a concave cylindrical face which has an edge approximately engaged by the cylinder of revolution of said portions of the cutting edges and which forms a tapered opening with said cylinder of 15 revolution, said anvil being provided with another face which is substantially continuous with said cylindrical face and which extends away from the cutter and forms with the surface of revolution of other portions of the cutting edges 20 of the cutter a throat through which work such, for example, as a projecting margin of a cover secured to a heel, may be fed into said tapered opening. The anvil may be swung into different adjusted positions about an axis which is substantially parallel to the axis of rotation of the 25 cutter and extends along said edge of the concave cylindrical face of the anvil, in order to vary the width of the tapered opening in accordance with the thickness of the cover margin. By providing the anvil of the above machine with a concave cylindrical face which is adjustable about said axis it is possible quickly and effectively to 30 skive projecting cover margins to a uniform width equal to the length of said face, irrespective of 35 the thickness of the cover margin.

40 The various features of the invention will be understood and appreciated from the following detailed description read in connection with the accompanying drawings, in which

45 Fig. 1 is a side view, partly broken away, of the illustrated machine;

Fig. 2 is a plan view of the machine, partly in section, on line II—II of Fig. 1;

50 Figs. 3 and 4 are illustrative views showing the top and the forward projecting margins of covers secured to heels in the process of being skived by the above machine;

55 Fig. 5 is a perspective view of an anvil for supporting the cover margin;

Fig. 6 is an enlarged front view of the anvil and a cooperating gage;

Fig. 7 is an enlarged side view showing in detail the construction of the anvil and the cutting edges of the cutter;

Fig. 8 is an enlarged section on line VIII—VIII of Fig. 1; and

Fig. 9 is a perspective view of a heel the skived projecting margins of the cover of which have been secured to the attaching face and the breast of the heel.

The illustrated machine is described with reference to skiving the top and forward projecting margins 20 (Fig. 3), 22 (Fig. 4) of a leather cover 24 which is cemented or otherwise secured to the side and rear faces of a Louis heel 26, preparatory to securing the respective margins to the attaching face 28 and the breast 30 of the heel.

The projecting margin 20, 22 of the cover is supported by an anvil 32 as the heel and the projecting margin of its cover are guided by a gage 34 and the anvil past a rotary cutter 36, the projecting margin being skived to a uniform width by cutting edges 38 of the cutter.

The cutter is secured by a screw 40 (Figs. 1 and 2) to a drive shaft 42 (Fig. 2) and is provided with a plurality of skewed blades 44 which have about 8° of front rake. Each cutting edge 38 of the cutter comprises a leading portion 48 (Figs. 7 and 8) which is curved toward the axis 50 30 (Figs. 2 and 8) of rotation of the cutter, and a trailing portion 52 which is equidistant from said axis.

The cutter 36 is housed in a casing 54 (Figs. 1 and 2) which is secured by screws 56 to a bed 35 plate 58 and is provided with an air duct 60. The left end of the duct 60 is connected to a suitable source of suction to insure against leather dust and chips depositing upon the flesh side of the cover margin which is usually coated with cement. In order further to insure against the depositing of leather dust on the flesh side of the cover margin there is provided a tube 60 through which air is introduced into a gap 62 (Fig. 1) formed between the gage 34 and the anvil 32. 45

The gage 34 is pivoted to a carrier 64 (Fig. 1) which fits in an arcuate groove 66 formed in the casing 54 and has an elongated slot 68 for receiving a screw 70 threaded into the casing. The carrier 64 is also provided with a lug 72 into 50 which is threaded a screw 74 which passes through an opening in an extension 76 of the gage 34, the extension being forced against the head of the screw 74 by a spring 78. By moving the carrier 64 into different adjusted positions 55

along the arcuate groove 66 which is centered about the axis 50 of rotation of the cutter 36, and turning the screw 74 to swing the gage 34 with relation to the carrier 64, the lower end 5 of the gage may be initially adjusted to its proper position with relation to the anvil 32.

The lower portion of the anvil 32 fits between bifurcations of a slide 80 which is movable into different adjusted positions along a guideway 82 10 of the bed plate 58. The lower end of the anvil 32 is provided with an arcuate slot 84 of suitable size to receive rolls 86 which engage the upper face of said slot and are mounted upon screws 88 threaded into the slide 80. A roll 90 mounted 15 upon an eccentric portion of a screw 92 is forced against the lower face of the arcuate slot 84 by turning the screw which may be secured in different adjusted positions in the slide 80 by a nut (not shown). The anvil 32 may be adjusted into 20 different angular positions with reference to the slide 80 by releasing the screws 88 and turning a thumb screw 94 against the end of which a depending lug 96 of the anvil is forced by a spring 98. After the above adjustment has been effected 25 the screws 88 are again tightened causing the anvil 32 to be clamped to the slide 80. The slide 80 is moved into different adjusted positions along the guideway 82 by a thumb screw 100 which is pivoted to the bed plate 58 and is threaded into 30 the slide. To insure against the turning of the adjusted screw 100 there is provided a binding spring 102. As will later appear, the arcuate slot 84 is centered about an axis 104 (Figs. 5 and 8) which is parallel to the axis 50 of rotation of the 35 cutter and extends along the lower edge 106 (Fig. 5) of a concave cylindrical face 108 (Figs. 5, 7 and 8) of the anvil 32. When the anvil 32 is in its operative position the trailing portions 52 of the cutting edges just miss the edge 106 of the 40 face 108 during the rotation of the cutter 36. In order to close up an opening 109 (Fig. 2) formed between the anvil 32 and the casing 54 the anvil has secured to it a curved plate 111.

In skiving the top projecting margin 20 of the 45 cover 24 (Fig. 3) it is desirable that the skiving cut extend to line 110 (Figs. 3 and 9) which lies within the rim of the attaching face of the heel thereby insuring that the skived portion of the margin shall not be visible in the finished shoe. 50 In skiving the forward projecting margins of covers (Fig. 4), however, it is desirable to have the skiving cut extend to the breast edge 112 (Figs. 4 and 9) of the covered heel since it is difficult effectively to cement the heel-breast covering flap (not shown) to the grain surface of the 55 cover margin.

In order to adjust the machine for skiving cover margins 20, 22 the operator turns the thumb screw 100 (Figs. 1 and 2) causing the anvil to approach the cutter until the lower edge 106 of its concave cylindrical face 108 is approximately engaged by the trailing portions 52 of the cutting edges when the cutter is rotated. The anvil is then angularly adjusted with relation to the slide 80 after releasing screws 88, by turning the thumb screw 94 until the tapered opening 114 (Fig. 7) formed between the face 108 of the anvil and the cylinder of revolution 116 of the trailing portions 52 of the cutting edges is of sufficient width to 60 insure the starting of the skiving cuts along line 110 (Fig. 3) or at the breast edge 112 (Fig. 4) of the covered heel, the above adjustment varying in accordance with the thickness of the cover margin. The opening 114 (Fig. 7) may be described as tapering circumferentially of the cut- 65

ter toward the edge 106 of the anvil 32. The gage 34 is then adjusted to its proper position with relation to the anvil 32 through the provision of the above-described mechanism, the position of said gage being varied in accordance with 70 the shape of the heel and whether the top or the forward projecting margin of the cover is to be skived.

It is desirable that the skived margins be wide enough to insure that when they are laid upon 75 the attaching and breast faces, respectively, of the heel no abrupt changes in the curvature of said faces shall appear. Skived portions of leather absorb glue or cement by which the heel is attached to the shoe upper and the flap is attached 80 to the breast of the heel, more readily than the grain surface of leather. It is therefore desirable, as above stated, in skiving the forward projecting margin 22, that the cuts extend to the breast edge of the heel since the lateral margins 85 of the heel-breast covering flap of the finished shoe have a tendency to break away from the breast of the heel when they are secured to in-turned grain surfaces of the cover margin. Care should be taken, however, as previously explained, 90 to insure that in skiving the top projecting margin the skiving cuts shall not extend too close to the rim of the heel.

With the above considerations in view, the 95 radius of curvature of the cylindrical concave face 108 of the anvil 32 is equal to or preferably slightly less than the radius 118 (Figs. 1 and 8) of the cutter 36. With such a construction it will be clear that the anvil 32 may be adjusted about said axis 104 (Figs. 5 and 8) into close proximity 100 to the cylinder of revolution 116 (Fig. 7) of the trailing portions 52 of the cutting edges of the cutter without interfering with said cutter, thereby insuring that very thin as well as thick covers may be skived to a uniform width approximately 105 equal to the heightwise dimension of the face 108 of the anvil 32. By providing an anvil 32 having a concave cylindrical face 108 which approximates the path of movement of the trailing portion 52 of the cutting edge, it has been found that 110 the projecting margin may be beveled to a predetermined width with a minimum amount of drag on the cover. In order to insure that the edge of the skived projecting margin of the cover shall be feathered to a well-defined line the anvil 115 is provided with a narrow shoulder 122 for supporting the cover margin extending below the edge 106.

The anvil also comprises a sole-engaging face 124 (Figs. 7 and 8) which curves away from the 120 cutter and forms with the surface of revolution of said portions 48 of the cutting edges, a throat 126 through which the projecting margin is fed into the tapered opening 114. The face 124 is continuous with the concave cylindrical face 108, 125 said faces constituting the work-supporting face of the anvil 32. The top edge 128 of the anvil 32, which serves as a gage and cooperates with the gage 34 in guiding the heel and the projecting margin of its cover past the cutter 36, is sharply 130 curved, as best shown in Fig. 6, in order to accommodate the sharply curved breasts of Louis heels.

In order to skive the forwardly projecting margin 22 of the cover 24 the heel is positioned with the lateral portion of its breast in engagement 135 with the edge 128 (Figs. 5 and 7) of the anvil and with its side in engagement with the gage 34, the projecting margin being inserted in the gap 62 (Fig. 1) formed between the anvil 32 and the gage 34. The heel guided by the anvil 32 and the gage 75

34 is moved past the cutter, the projecting margin being progressively bent toward the anvil by the leading portions 48 of the cutting edges of the cutter and then being forced against the concave 5 cylindrical face of the anvil as it is skived to a predetermined width by the trailing portions 52 of the cutting edges. The cutting strokes of the cutting edges of the cutter progress toward the edge of the margin and tension the same as it is 10 skived. In skiving the top projecting margin 20 (Fig. 3) of the cover the gage 34 is adjusted to the position illustrated in Fig. 3 so that the skiving cut shall lie within the rim of the attaching face 28, for reasons above explained. The heel and 15 the top projecting cover margin are then fed past the cutter in the manner above described to skive said margin.

Having described the invention, what I claim as new and desire to secure by Letters Patent of 20 the United States is:

1. A skiving machine having, in combination, a cutter rotatable about an axis, said cutter having a plurality of cutting edges portions of which are equidistant from said axis, means for rotating 25 the cutter, and an anvil having a concave cylindrical face which has an edge approximately engaged by the cylinder of revolution of said portions of the cutting edges and which forms with said cylinder of revolution an opening tapering 30 circumferentially of the cutter, said anvil having another face which is substantially continuous with said first-named face and extends away from the cutter and forms with the surface of revolution of other portions of said cutting edges 35 of the cutter a throat through which work to be skived is fed into said tapered opening.

2. A skiving machine having, in combination, a rotary cutter having a plurality of cutting edges, means for rotating said cutter, an anvil 40 having a face for supporting a margin of a flexible piece of material against the action of said cutter, a portion of said face having an edge

which is approximately engaged by portions of said cutting edges during rotation of the cutter, said portion of the face being concave circumferentially of the cutter and forming a tapered opening with the surface of revolution of said 5 portions of the cutting edges, another portion of said face forming with the surface of revolution of other portions of said cutting edges a throat through which said margin is fed into said tapered opening, and means for swinging said anvil 10 into different adjusted positions about an axis which is substantially parallel to the axis of rotation of said cutter and extends along said edge of the concave cylindrical face of the anvil thereby to vary the width of the tapered opening in accordance with the thickness of the margin to be 15 skived.

3. In a machine for skiving to a predetermined width a projecting margin of a cover secured to a heel, a rotary cutter having a plurality of cutting 20 edges, an anvil having a face for supporting said margin against the action of the cutter, said face comprising a concave cylindrical portion extending circumferentially of an adjacent portion of the surface of revolution of said cutting edges and 25 having an edge approximately engaged by portions of said cutting edges, said cylindrical portion having a radius of curvature approximately equal to the radius of the cutter and forming with the surface of revolution of portions of said cutting edges an opening tapering circumferentially of the cutter, and other portions of said face of the anvil forming with the surface of revolution of other portions of said cutting edges a 30 throat which tapers in the general direction of 35 the axis of rotation of the cutter and through which the margin is fed into said tapered opening, and means comprising said anvil for guiding the heel and the projecting margin of its cover past the cutter.

LEWIS J. BAZZONI.
